ABRADING MACHINE

Arthur N. Emmons, Syracuse, N. Y., assignor to
 The Porter-Cable Machine Company, Syracuse,
 N. Y., a corporation of New York

Application March 20, 1931. Serial No. 524,077

2 Claims. (Cl. 51—174)

This invention relates to abrading machines, and has for its object, a particularly simple and efficient abrading roller construction, whereby the roller distorts or bulges and flattens out of 5 a cylindrical curve when pressure is applied to the roller, for the purpose of projecting a front portion of the roller forwardly in order that the abrading operation may be performed up nearer a wall, and leave a smaller unfinished surface 10 than when the rollers heretofore used are employed, and without the use of an additional element or nose in front of the roller.

The invention consists in the novel features and in the combinations and constructions hereinafter set forth and claimed.

In describing this invention, reference is had to the accompanying drawings, in which like characters designate corresponding parts in all the views.

20 Figure 1 is a fragmentary elevation of a portable abrading machine embodying this invention.

Figure 2 is an enlarged sectional view through the roller, the contiguous portion of the supporting frame therefor being also shown.

25 Figure 3 is an enlarged front elevation of the roller and contiguous parts.

The invention is here shown in a portable sanding or surfacing machine wherein an abrading belt runs over front and rear rollers. The general construction of the machine is substantially 30 as shown in my pending application, Sr. No. 118,660, filed June 26, 1926, which has matured into Patent Number 1,821,624 granted September 1, 1931.

35 The body of the machine comprises a main frame 1, and supporting means for front and rear rollers 2, 3, the front roller being carried by a frame or carriage 4 having a guide 5 movable in a guide passage 6 formed in a block 7 rigid 40 with the main frame 1, the carriage being pressed forwardly by means of a spring 8 and being adjusted by means of a nut 9 screwing on the threaded end of a stem 10 extending axially into the passage 6 and secured at 11 to the end of an 45 guide 5. The spring 8 encircles the rod or stem 10. The front roller 2 is mounted on an axle 12 supported at one end by the carriage or frame 4, and capable of a slight angular adjustment, it being shown as pivoted at one end at

50 13 to the frame or carriage 4, and as adjustable within limits about its pivot for alining the roller to cause the belt to run straight by means of an arm 14 fixed to the end of the axle 12 and adjustable by means of a thumb screw 15.

55 The rear roller 3 is mounted on a suitable axle

16 supported by the frame 1 and is actuated through suitable motion transmitting means from an electric motor mounted on the frame, which motor is housed within a casing 17. The body 60 is provided with a suitable handle 18 at its rear end, and with a knob or handle 19 at its front end.

27, over which the upper run of the belt runs, the cross bar being provided with a shallow channel 28 for guiding the belt, or the upper run thereof. The shoe 22 is of sufficient height over the belt to permit a limited crushing or distorting of the roller 2. An adjustable bumper 30 extends across the front end of the carriage 4 above the roller 2 to prevent the abrading belt from engaging the wall or mop-board when the front end of the machine is pushed up close to the wall or mop-board. As the bumper 30 is supported by the carriage 4, it partakes of the adjustments thereof effected by the nut 9.

In operation, the operator moves the tool over 15 the floor, but when the tool approaches a wall, as seen in Figure 1, he can bear down heavier on the knob or handle 19, causing the roller 2 to distort and flatten, as shown in Figure 1, so that the roller will press the abrading belt up fairly close 20 to the wall, or the molding 29, leaving a minimum margin to be finished by hand. Of course, during the normal operation, pressure can be applied to the roller 2 by means of the knob or handle 19 to cause it to distort, but the distortion is primarily of importance when working up close 25 to a wall.

What I claim is:

1. A portable abrading machine of the type described including a frame, a rear roller journalled in the frame and extending transversely thereof, 30 a carriage supported by the frame and being

movable axially of the frame toward and from the rear roller, a second roller journalled at the forward end of said carriage and extending transversely of the frame, said second roller being of lesser diameter than the rear roller and being formed in part of sufficient yielding material and being capable while the machine is in operation of flattening out on the surface being finished so that the flattened portion is of greater width than the radius of the roller, an abrading belt trained over the rollers, a presser shoe carried by the carriage behind and adjacent the forward roller and having its lower side contacting with the lower run of the abrading belt, and means for actuating the rear roller.

2. A portable abrading machine of the type described including a frame, a rear roller journalled in the frame, a carriage supported at the forward end of the frame and being movable axially of the frame toward and from the rear roller, a forward roller journalled to the carriage, an abrading belt trained about the rollers, a presser shoe also carried by the carriage behind and adjacent the forward roller and having its lower side in contact with the lower run of the abrading belt, a rest secured to the rear of the frame for supporting the same and the rear roller from the surface being finished, and means carried by the frame for actuating the rear roller.

ARTHUR N. EMMONS.
